APPARATUS FOR PREPARING CERAMIC ARTICLES

Willy Lengersdorff and Max Lengersdorff,
Bunzlau, GermanyApplication May 31, 1929, Serial No. 367,450, and
in Germany February 9, 1928

1 Claim. (Cl. 25—2)

The subject of the present invention forms a process for the mechanical manufacture of ceramic articles.

The new and essential feature consists in the fact that the articles are shaped, polished, grooved and dried on a moving band without changing of position, so that any handling for local moving of the articles is avoided.

It has already been proposed in the ceramic industry to spread the ceramic masses on a forwarding band and to move it forward. It has also been proposed, to arrange casting moulds on a band and to move this forward under a pouring apparatus.

15 The present invention on the other hand, contemplates avoiding the otherwise unavoidable frequent moving about of the articles between the time when they are shaped and fired. This repeated moving about means not only considerably increased work, but also an extraordinary deterioration of the finished product, and consequently the present continuous forward moving band offers not only a cheapening of manufacture, but also a lessening of waste and simultaneously a considerable increase in the quality of the finished product.

When the tubes, which in the drying room stand in piles of 100 to 200 articles, receive during drying a draft of air on one side, this side dries prematurely and the tubes become curved. Consequently, with the present day methods of drying, the articles must be changed several times and so that the straight tubes come to rest in the middle of the pile, whilst in the outer rows of the pile the curved, already dried articles must be arranged with the curved parts outwards. The result of this method of manufacture is that perhaps the articles curved through drying will draw out in the right direction, but perhaps will 40 curve out towards a second side.

Not only the repeated changing, but also particularly the forwarding of the articles to the oven gives rise to great waste. Further, with the working method in piles in use up to the present, the outer articles are accessible to observation, on the other hand the tube arranged in the inside can hardly be observed and controlled and even when a mistake has been observed the changing 45 of position of the faulty article is so extraordinarily difficult, that in normal factory practice it is not done.

Figure 1 is a cross-section through the apparatus for the present process.

55 Figure 2 shows diagrammatically a longitudi-

nal section through the apparatus after removing the insulating hoods or covers.

In accordance with the present invention the work from the molding machine to the entrance to the oven is completely effected on one work 60 table and so that the articles are not subjected to any movement in relation to the work table. For this purpose a work table is arranged directly on to the molding machine. This consists of a frame *a* with rollers *b*. The rollers *b* rotate 65 in bearings *c*. Near the upper edges of the rollers, guide plates *d* are arranged. Between these guide plates on the rollers *b* lie the carrying boards *e*, on which the separate moulded articles *f* rest. Underneath the rollers *b* is mounted the heating tube *g*. At those places at which no working or controlling of the articles is necessary, the guide plates *d* carry an asbestos cover *h* in order to concentrate the heat. A tube put 70 down on the carrying boards *e* of the work table 75 can easily be moved forward by hand or by mechanical means. The breadth of the table depends on the articles, the length on the day's production or the length of the drying process. The carrying boards *e* can also be provided with 80 a disk *i* in the manner of a potter's lathe.

If, for example, tubes are to be produced, the tube molded by the molding machine and provided with grooves is lifted from the machine in such a manner that it rests with its pointed end 85 on the so-called base board *e'*. The base board with the tube is now removed from the molding machine direct on to the beginning of the work table. The formed tube is now molded again and moves forward with its base board on the work 90 table so that it is automatically pushed one step forward, when the second tube, pressed, and otherwise treated moves into the position of the first one.

The formed articles move, through the continual pushing, over the rollers of the work table, until they arrive at the oven. The heating of the work table, particularly the heat insulation *h*, gives an excellent, even, rapid drying, without the articles being piled, changed and thereby 100 damaged or crooked.

The heat insulation *h* can also be formed as a drying arrangement in accordance with the known damp system.

As a further sphere of application the preparation of sanitary articles, such as closet basins, wash basins, and particularly baths, can be mentioned. Here it is immaterial whether the moulding is done by pouring or by hand. The whole process from the moulding to the entry into the 105

oven, including the glazing of the crude articles occurs on the work table.

The possibility of controlling each article as well by the workman as by the overseer is of the greatest importance. The control by the overseer forces the worker to prepare the articles particularly carefully. Any deformations or formation of cracks can no longer be excused, but become in fact immediately apparent.

10 Even with deficient execution it is now possible to preserve from crookedness and cracks articles, which perhaps dry on one side, by timely laying on of damp cloths, in the known manner.

15 The present production process enables all working and drying faults to be removed at the instant they occur.

We claim:—

Apparatus for continuously manufacturing ceramic articles, comprising a work table including roller members, forming a continuous path having supporting boards for the molded articles, which path is adapted to convey the articles during the whole process from the moulding to the entry into the oven, a heating means below the entire path adapted to heat the articles on the supporting boards during the whole process, lateral guides for the supporting boards on the path, and removable hoods adapted for the continuous control of the articles to be manufactured.
